UNITED STATES PATENT OFFICE.

EDWARD M. MOLLER, OF HOBOKEN, NEW JERSEY.

PASSENGER-CAR.

994,183.

Specification of Letters Patent. Patented June 6, 1911.

Application filed April 22, 1910. Serial No. 556,942.

To all whom it may concern:

Be it known that I, EDWARD M. MOLLER, a subject of the King of Norway, residing at Hoboken, in the county of Hudson and State 5 of New Jersey, have invented certain new and useful Improvements in Passenger-Cars; and I do hereby declare the following to be a full, clear, and exact description of the invention, such as will enable others 10 skilled in the art to which it appertains to make and use the same, reference being had to the accompanying drawings, and to characters of reference marked thereon, which form a part of this specification.

15 This invention has reference, generally, to improvements in door-operating mechanisms for the platforms of railway cars; and, the invention relates, more particularly, to a novel arrangement of door or doors for the 20 rear platforms of that class of street-railway cars, known as "pay-as-you-enter" cars, or "enter and pay-within" cars.

The present invention relates, furthermore, to a novel mechanism for operating a 25 pair of hinged or foldably arranged door-sections, which when the entrance and exit- 30 portions of the platform are free or open stand in their folded relation in a plane extending laterally across the platform, that is in a direction from side to side of the car-body, but when the entrance and exit-portions at the step of the platform are closed, the said hinged or foldably connected doors 35 standing in an extended or opened-out relation in a plane extending in a longitudinal direction of the body of the car and at the side of the platform of the car, at or near the step-portion of the platform.

The present invention, therefore, has for 40 its principal objects to provide in connection with the types of street-railway cars known as "pay-as-you-enter" cars, and the "enter and pay-within" cars, a novel arrangement and simple and efficient construction of door 45 or doors and mechanism for operating the same, so as to open or close the door or doors, said mechanism being under the perfect control of the conductor.

Other objects of this invention not at this

time more particularly enumerated will be 50 clearly understood from the following detailed description of my present invention.

The present invention consists, primarily, in the novel door or doors for the platforms of street railway cars, as well as in a novel 55 mechanism for operating the same, and of the character hereinafter more fully set forth; and, the invention consists, furthermore, in the novel arrangements and combinations of the various devices and parts, 60 as well as in the details of the construction of the same, all of which will be more fully described in the following specification, and then finally embodied in the clauses of the 65 claim which are appended to and which form an essential part of this specification.

The invention is clearly illustrated in the accompanying drawings, in which:—

Figure 1 is a transverse vertical section of the rear platform of a car, looking toward the car-body, and showing in elevation the folded arrangement of the door-sections, when the door has been opened, and said view illustrating, furthermore, in elevation one form of mechanism operated by the conductor for opening and closing the door. Fig. 2 is a diagrammatical horizontal sectional representation of the vestibule of the platform and a portion of the car-body, the platform, as well as the door-sections and 75 the door-operating mechanism being moved from the top, said view showing the door-sections in their separated relations when in the respective positions for closing both the 80 in and out or entrance and exit portions at 85 the side of the car-platform. Fig. 3 is a detail face view, on an enlarged scale, of the upper portions of the hinged or foldable door-sections, and the arrangement of the rails and door-hangers for said door-sections, looking in the direction of the arrow α in said Fig. 2. Fig. 4 is a view similar to that shown in said Fig. 2 of an arrangement of hinged or foldable door-sections embodying the principles of the present invention, but instead of a manually operated door-actuating or operating mechanism, said 95 view showing in lieu thereof a pneumatic

door-actuating or operating mechanism, said view representing the door-sections in their folded and opened relation; and Fig. 5 is a diagrammatical horizontal sectional representation of a portion of the platform vestibule and car-body, and a plan or top view of the platform and the door-sections, the latter being represented in their closed relations when closing both the entrance and exit-portions of the platform.

Similar characters of reference are employed in all of the above described views, to indicate corresponding parts.

Referring now to the said drawings, the reference-character 1 indicates the main body of the usual type of street-railway passenger car, and 2 indicates the end-wall of said body, said end-wall having a large opening 3 which provides the usual entrance from the rear platform 4 into the interior of the car-body. At the one side, the said platform is provided with a step 5, and the reference-character 6 indicates the frame-work of the vestibule which incloses the said platform. The platform may also be provided with any suitably formed dividing rail, as 7, which divides the platform into an "in" or entrance portion and an "out" or exit-portion 9, and 10 indicates a fare-receiving box of any usual construction, such as is ordinarily placed upon the platforms of cars of the "pay as you enter" type.

The position of the conductor is at one side of the fare-receiver and in close proximity to a lever or handle for operating the door-opening and closing mechanism in the manner to be hereinafter more fully described.

40 The platform hood is indicated by the reference-character 11, and 12 represents one of the rafters for supporting said hood. Suitably secured to the rafters 12 is a suitable bar or plate-like element, as 13, to which are suitably secured and extend downwardly therefrom a pair of brackets 14 and 15. Suitably secured to the lower portion of the said bracket 14 is a laterally extending track or rail 16, said track or rail terminating at a point approximately above the step 5 of the platform, said end-portion of the track or rail being suitably secured to and supported by the members 17 and 18 which form parts of the hood-supporting construction. Suitably secured to the said members 17 and 18 are a pair of tracks or rails, as 19 and 20, said tracks or rails 19 and 20 being located at points approximately above the step 5, and extending longitudinally of the main body of the car, said tracks or rails 19 and 20 being respectively formed near the track or rail 16 with the curved end-portions 22 and 23 which terminate on opposite sides of the track or rail 16, and in close proximity thereto, as

clearly indicated in the several figures of the drawings.

The door consists, essentially, of a pair of door-sections 24 and 25, said doors being foldably connected by means of hinges 26, see Fig. 1 of the drawings, and an upper hinge 27, one of the hinge-plates of said hinge 27 being made with a tubular member or hub 28. Movable arranged in said tubular member 28, so as to be adapted to oscillate therein, is a pin or stem 30 of a hub 29, said hub 29 resting upon the tubular member 28 and the parts being retained in their assembled relation by a suitable pin, as 31, arranged in and extending directly across the stem 30 beneath the tubular member or hub 28, substantially as shown in Fig. 3 of the drawings. Extending upwardly from said hub 29, and at the one side of the rail or track 16, is a bracket-like post or arm 32, formed at one side with a bifurcated portion 33, and upon its opposite side with a frame-like element 34 forming the carriage of a pair of grooved wheels or rollers 35 which are mounted and are adapted to roll upon the upper edge of the said laterally extending track or rail 16. The said bifurcated portion 33 carries a pin or pintle 36, with which is pivotally connected, in any suitable manner, the one end-portion of a link or rod 37. The opposite end-portion of the said link or rod 37 is pivotally connected by means of a pin 38 with an end of a short arm or link 39, which in turn is pivotally connected at its opposite end-portion by means of a pin 40 with a suitably formed bracket, as 41, which is suitably secured to and extends at the proper place from the end-wall 2 or other suitable part of the car-body. Suitably secured upon the platform is a post or standard, as 42, to which is suitably secured and is mounted thereon a yoke-shaped member or element, as 43, said member or element being provided with a bearing-portion 44. Extending from the bracket 15, and in alinement with the bearing-portion 44, is a bearing-portion 45. Oscillately mounted in said bearing-ports 44 and 45 is a rod or stem 46, said rod or stem 46 being arranged within a tubular member or pipe 47, substantially as shown in Fig. 1 of the drawings. Suitably secured upon the lower end-portion of the rod or stem 46 which extends below the bearing-portion 44 is the operating or actuating handle or lever 48, hereinbefore mentioned, and suitably secured upon the upper end-portion of the rod or stem 46 which extends above the bearing-portion 45, is a crank or lever 49 which is provided with a stud or pivot-post 50. A connecting rod or link 51 is pivotally connected at one end with said stud or pivot 50, said rod or link 51 being pivotally connected at its other end by means of a stud or pivot-post 52 with the previously mentioned 130

link or rod 37. The operation of these various parts will be self-evident from an inspection of Figs. 1, 2 and 3 of the drawings.

5 Referring now to Figs. 2 and 3, it will be seen, that the said door-sections 24 and 25, are provided at their upper edges with suitable plates, as 58, each plate being formed with an upwardly extending socket 54. 10 Pivots arranged in each socket 54 is a pintle or pivot-post 55, the upper end-portion of each post 55 extending into and being suitably secured in a bearing-portion or receiving socket 57 of a carriage 56. Said 15 carriages of which there are two, one for each rail or track 19 and 20, are provided with laterally extending pins, as 58, and mounted upon each pin 58 is a grooved wheel or roller 59. Each carriage is 20 preferably provided with two of such wheels or rollers 59, and each pair of rollers or wheels 59 of the respective carriages 56 is placed in rolling contact upon the upper edges of the respective rails or tracks 19 and 20. 25 From an inspection of the several figures of the drawings, it will be clearly evident, that by the proper manipulation of the handle or lever 48, and the arrangement of the wheels or rollers 35 upon the laterally 30 extending track or rail 16, and the wheels or rollers 59 upon the respective curved and longitudinally extending tracks or rails 19 and 20, the door-sections 24 and 25 can be brought into their folded and opened position with relation to the entrance and exit-portions of the platform, or they can be brought into their extended and closed position with relation to said entrance and exit-portions of the platform. The said 35 40 door-sections 24 and 25, if desired, may be provided with handles or gripping devices, as 60.

If desired, the said door-sections 24 and 25, as will be seen from an inspection of 45 Figs. 4 and 5, may be brought into their opened and closed positions by means of pneumatic or air-controlled devices. One form of such air-controlled devices is diagrammatically represented in Fig. 4 of the 50 drawings, and comprises a cylinder 61 in which is slidably arranged a piston or plunger 62, said piston or plunger being provided with a piston-rod 63 which extends through a closed end-portion or head 55 of said cylinder 61, and is operatively connected with the frame-like element or carriage 34 carrying the wheels or rollers 35 which roll upon the rail or track 16. The reference-character 64 indicates a suitably 60 constructed compressed air-receiving device or controller, which is provided with a suitably formed two-way valve, operated by means of a suitable handle or lever 65. An air-inlet pipe 66 is connected with said device 64 for admitting compressed air to said

valve, and the reference-characters 68 and 69 are leading-out pipes arranged between said device 64 and the respective end-portions of said cylinder 61, said pipes 68 and 69 acting respectively and alternately as inlet and 70 exhaust pipes to and from said cylinder 61, as will be clearly evident. The reference-character 67 indicates an exhaust pipe which is suitably connected with the device or controller 64. The remaining devices and parts 75 of the door-operating mechanism, for bringing the door-sections into their closed and opened relations is the same as that described in connection with the construction shown in Figs. 1, 2 and 3 of the drawings, 80 and need not, therefore, be further described. The operations of the various devices and parts of the air-controller will be clearly understood from an inspection of said Fig. 4.

I am fully aware that some changes may 85 be made in the arrangements and combinations of the various devices and parts, without departing from the scope of the present invention as set forth in the foregoing specification and as defined in the claims 90 which are appended thereto. Hence, I do not limit my present invention to the exact arrangements and combinations of the devices and parts, as described in the said specification, nor do I confine myself to the 95 exact details of the construction of the parts as illustrated in the accompanying drawings.

I claim:—

1. A car provided with a car-body and a platform, said platform having a step, 100 and said platform being provided with an entrance and an exit-portion, a door for opening and closing said entrance and exit-portion, said door comprising foldably connected door-sections, said sections when folded extending laterally across a portion of the platform so as to separate the entrance-portion from the exit-portion of the platform, and the said door-sections when in their extended relation extending longitudinally of the platform and closing the entrance and exit-portion near the step, and a door-operating mechanism under the control of the conductor upon the platform for sliding the said door-sections and bringing the same either into their folded or extended relations, consisting of a series of tracks, and carriages secured to said door-sections, said carriages being provided with rollers running upon said tracks, a vertically disposed rod, a handle secured upon said rod for producing oscillatory movements of said rod, and a lever-mechanism between said rod and one of said carriages, substantially as and for the purposes set 115 forth.

2. A car provided with a car-body and a platform, said platform having a step, 120 and said platform being provided with an entrance and an exit-portion, a door for 125

opening and closing said entrance and exit-
portions, said door comprising foldably con-
nected door-sections, said sections when
folded extending laterally across a portion
5 of the platform so as to separate the en-
trance-portion from the exit-portion of the
platform, and the said door-sections when
in their extended relation extending longi-
tudinally of the platform and closing the
10 entrance and exit-portions near the step,
and a door-operating mechanism under the
control of the conductor upon the platform
for sliding the said door-sections and bring-
ing the same either into their folded or ex-
15 tended relations, consisting of a series of
tracks, and carriages secured to said door-
sections, said carriages being provided with
rollers running upon said tracks, a verti-
cally disposed rod, a handle secured upon
20 said rod for producing oscillatory move-
ments of said rod, a crank connected with
the said rod, a bracket secured to a portion
of the car-body, an arm pivotally connected
with said bracket, a link pivotally connected
25 at one end to said arm and at the other end
to one of said carriages, and a connecting
rod pivotally connected at one end to said
link and at the other end to said crank, sub-
stantially as and for the purposes set forth.
30 3. A car provided with a car-body and a
platform, said platform having a step, and
said platform being provided with an en-
trance and an exit-portion, a track arranged
beneath the platform-hood and extending
35 laterally across a portion of the said plat-
form, and a pair of other tracks extending
longitudinally of the platform on opposite
sides of said laterally extending track, each
longitudinally extending track having
40 curved end-portions terminating in close
proximity upon each side of the said later-
ally extending track, a door for opening
and closing said entrance and exit-portions,
hinges secured to said door-sections for
45 foldably connecting said door-sections, a
bracket-like post extending upwardly from
one of said hinges, a carriage connected with
said post, grooved rollers mounted in said
carriage, said grooved rollers running upon
50 said laterally extending track, posts extend-
ing upwardly from each door-section, a
swiveled carriage connected with each of
said last-mentioned posts, and rollers mount-
ed in said swiveled carriages, the rollers of
55 ers of the respective swiveled carriages run-
ning upon the respective longitudinally ex-
tending tracks, all arranged so that said
door-sections when folded will extend later-
ally across a portion of the platform so as
60 to separate the entrance-portion from the
exit-portion of the platform, and that the
door-sections when in their extended rela-
tion will extend longitudinally of the plat-
form so as to close the entrance and exit-
65 portions near the step.

4. A car provided with a car-body and a
platform, said platform having a step, and
said platform being provided with an en-
trance and an exit-portion, a track arranged
beneath the platform-hood and extending
70 laterally across a portion of the said plat-
form, and a pair of other tracks extending
longitudinally of the platform on opposite
sides of said laterally extending track, each
longitudinally extending track having a
75 curved end-portion terminating in close prox-
imity upon each side of the said laterally
extending track, a door for opening and
closing said entrance and exit- portions,
hinges secured to said door-sections for fold-
80 ably connecting said door-sections, a bracket-
like post extending upwardly from one of
said hinges, a carriage connected with said
post, grooved rollers mounted in said car-
riage, said grooved rollers running upon
85 said laterally extending track, posts ex-
tending upwardly from each door-section, a
swiveled carriage connected with each of
said last-mentioned posts, and rollers mount-
ed in said swiveled carriages, the rollers of
90 the respective swiveled carriages running
upon the respective longitudinally extend-
ing tracks, all arranged so that said door-
sections when folded will extend laterally
across a portion of the platform so as to
95 separate the entrance-portion from the exit-
portion of the platform, and that the door-
sections when in their extended relation
will extend longitudinally of the platform
so as to close the entrance and exit- portions
100 near the step and a door-operating mech-
anism under the control of the conductor
upon the platform for sliding the said door-
sections and bringing the same either into
their folded or extended relations.
105 5. A car provided with a car-body and a
platform, said platform having a step, and
said platform being provided with an en-
trance and an exit-portion, a track arranged
beneath the platform-hood and extending
110 laterally across a portion of the said plat-
form, and a pair of other tracks extending
longitudinally of the platform on opposite
sides of said laterally extending track, each
longitudinally extending track having a
115 curved end-portion terminating in close
proximity upon each side of the said later-
ally extending track, a door for opening
and closing said entrance and exit- portions,
hinges secured to said door-sections for
120 foldably connecting said door-sections, a
bracket-like post extending upwardly from
one of said hinges, a carriage connected with
said post, groove rollers mounted in said
carriage, said grooved rollers running upon
125 said laterally extending track, posts extend-
ing upwardly from each door-section, a
swiveled carriage connected with each of
said last-mentioned posts, and rollers mount-
ed in said swiveled carriages, the rollers
130

of the respective swiveled carriages running upon the respective longitudinally extending tracks, all arranged so that said door-sections when folded will extend laterally across a portion of the platform so as to separate the entrance-portion from the exit-portion of the platform, and that the door-sections when in their extended relation will extend longitudinally of the platform so as 5 to close the entrance and exit-portions near the step, and a door-operating mechanism under the control of the conductor upon the platform for sliding the said door-sections and bringing the same either into their folded or extended relations, consisting of a vertically disposed rod, a handle secured upon said rod for producing oscillatory movements of said rod, and a lever mechanism between said rod and the post which 10 extends upwardly from one of the hinges of said door-sections, substantially as and for the purposes set forth.

6. A car provided with a car-body and a platform, said platform having a step, and said platform being provided with an entrance and an exit-portion, a track arranged beneath the platform-hood and extending laterally across a portion of the said platform, and a pair of other tracks extending 15 longitudinally of the platform on opposite sides of said laterally extending track, each longitudinally extending track having a curved end-portion terminating in close proximity upon each side of the said laterally extending track, a door for opening and closing said entrance and exit-portions, hinges secured to said door-sections for foldably connecting said door-sections, a bracket-like post extending upwardly from 20 one of said hinges, a carriage connected with said post, groove rollers mounted in said carriage, said grooved rollers running upon said laterally extending track, posts extending upwardly from each door-section, 25 a swiveled carriage connected with each of said last-mentioned posts, and rollers mounted in said swiveled carriages, the rollers of the respective swiveled carriages running upon the respective longitudinally 30 extending tracks, all arranged so that said door-sections when folded will extend laterally across a portion of the platform so as to separate the entrance-portion from the exit-portion of the platform, and that the door-sections when in their extended relation will extend longitudinally of the platform so as to close the entrance and exit-portions near the step, and a door-operating mechanism under the control of the conductor upon the platform for sliding the said door-sections and bringing the same either into their folded or extended relations, consisting of a vertically disposed rod, a handle secured upon said rod for producing 35 oscillatory movements of said rod, a

crank connected with said rod, a bracket secured to a portion of the car-body, an arm pivotally connected with said bracket, a link pivotally connected at one end to said arm and at the other end to the post which 40 extends upwardly from one of the hinges of said door-sections, and a connecting rod pivotally connected at one end to said link and at the other end to said crank, substantially as and for the purposes set forth.

7. A car provided with a car-body and a platform, said platform having a step, and said platform being provided with an entrance and an exit-portion, a door for opening and closing said entrance and exit-portions, said door comprising foldably connected door-sections, said sections when folded extending laterally across a portion of the platform so as to separate the entrance-portion from the exit-portion of the platform, and the said door-sections when in their extended relation extending longitudinally of the platform and closing the entrance and exit-portions near the step, and a door-operating mechanism under the control 45 of the conductor upon the platform for sliding the said door-sections and bringing the same either into their folded or extended relations, consisting of a series of tracks, and carriages secured to said door-sections, said carriages being provided with rollers running upon said tracks, a standard upon said platform, a yoke-shaped element secured upon said standard, a bracket, said bracket and said yoke-shaped element being provided with bearing portions, a pipe-like member arranged between said bearing portions, a vertically disposed rod mounted in said pipe-like member and said bearing portions, a handle secured upon the lower end-portion of said rod for producing oscillatory movements of said rod, and a lever-mechanism between said rod and one of said carriages, substantially as and for the purposes set forth.

8. A car provided with a car-body and a platform, said platform having a step, and said platform being provided with an entrance and an exit-portion, a door for opening and closing said entrance and exit-portions, said door comprising foldably connected door-sections, said sections when folded extending laterally across a portion of the platform so as to separate the entrance-portion from the exit-portion of the platform, and the said door-sections when in their extended relation extending longitudinally of the platform and closing the entrance and exit-portions near the step, and a door-operating mechanism under the control of the conductor upon the platform for sliding the said door-sections and bringing the same either into their folded or extended relations, consisting of a section of tracks, and carriages secured to said door-

sections, said carriages being provided with rollers running upon said tracks, a standard upon said platform, a yoke-shaped element secured upon said standard, a bracket, 5 said bracket and said yoke-shaped element being provided with bearing portions, a pipe-like member arranged between said bearing-portions, a vertically disposed rod mounted in said pipe-like member and said 10 bearing-portions, a handle secured upon the lower end-portion of said rod for producing oscillatory movements of said rod, a crank connected with the said rod, a bracket secured to a portion of the car-body, an arm 15 pivotally connected with said bracket, a link pivotally connected at one end to said arm and at the other end to one of said carriages, and a connecting rod pivotally connected at one end to said link and at the other end to 20 said crank, substantially as and for the purposes set forth.

9. A car provided with a car-body and a platform, said platform having a step, and said platform being provided with an entrance and an exit-portion, a track arranged beneath the platform-hood and extending laterally across a portion of the said platform, and a pair of other tracks extending longitudinally of the platform on opposite sides 25 of said laterally extending track, each longitudinally extending track having a curved end-portion terminating in close proximity upon each side of the said laterally extending track, a door for opening and closing said 30 entrance and exit-ports, hinges secured to said door-sections for foldably connecting said door-sections, a bracket-like post extending upwardly from one of said hinges, a carriage connected with said post, groove 35 rollers mounted in said carriage, said grooved rollers running upon said laterally extending track, posts extending upwardly from each door-section, a swiveled carriage connected with each of 40 said last-mentioned posts, and rollers mounted in said swiveled carriages, the rollers of 45 the respective swiveled carriages running upon the respective longitudinally extending tracks, all arranged so that said door-sections when folded 50 will extend laterally across a portion of the platform so as to separate the entrance-portion from the exit-portion of the platform, and that the door-sections when in their extended relation will extend longitudinally of the platform so as to close the entrance and exit-ports near 55 the step and a door-operating mechanism under the control of the conductor upon the platform for sliding the said door-sections and bringing the same either into their folded or extended relations, consisting of a 60 standard upon said platform, a yoke-shaped element secured upon said standard, a bracket, said bracket and said yoke-shaped element being provided with bearing-portions, a pipe-like member arranged between 65 said bearing-portions, a vertically disposed rod mounted in said pipe-like member and said bearing-portions, a handle secured upon the lower end-portion of said rod for producing oscillatory movements of said rod, a crank 70 connected with said rod, a bracket secured to a portion of the car-body, an arm pivotally connected with said bracket, a link

75 provided with bearing-portions, a pipe-like member arranged between said bearing-portions, a vertically disposed rod mounted in said pipe-like member and said bearing-portions, a handle secured upon the lower end-portion of said rod for producing oscillatory movements of said rod, and a lever-mechanism 80 between said rod and the post which extends upwardly from one of the hinges of said door-sections, substantially as and for the purposes set forth.

10. A car provided with a car-body and a platform, said platform having a step, and said platform being provided with an entrance and an exit-portion, a track arranged beneath the platform-hood and extending laterally across a portion of the said platform, and a pair of other tracks extending longitudinally of the platform on opposite sides of said laterally extending track, each longitudinally extending track having a 85 curved end-portion terminating in close proximity upon each side of the said laterally extending track, a door for opening and closing said entrance and exit-ports, hinges secured to said door-sections for foldably connecting said door-sections, a bracket-like post extending upwardly from one of said hinges, a carriage connected with said post, groove rollers mounted in said carriage, said grooved rollers running upon 90 said laterally extending tracks, posts extending upwardly from each door-section, a swiveled carriage connected with each of said last-mentioned posts, and rollers mounted in said swiveled carriages, the rollers of 95 the respective swiveled carriages running upon the respective longitudinally extending tracks, all arranged so that said door-sections when folded will extend laterally across a portion of the platform so as to 100 separate the entrance-portion from the exit-portion of the platform, and that the door-sections when in their extended relation will extend longitudinally of the platform so as to 105 close the entrance and exit-ports near the step and a door-operating mechanism under the control of the conductor upon the platform for sliding the said door-sections and bringing the same either into their folded or extended relations, consisting of a 110 standard upon said platform, a yoke-shaped element secured upon said standard, a bracket, said bracket and said yoke-shaped element being provided with bearing-portions, a pipe-like member arranged between 115 said bearing-portions, a vertically disposed rod mounted in said pipe-like member and said bearing-portions, a handle secured upon the lower end-portion of said rod for producing oscillatory movements of said rod, a crank 120 connected with said rod, a bracket secured to a portion of the car-body, an arm pivotally connected with said bracket, a link

pivotedly connected at one end to said arm and at the other end to the post which extends upwardly from one of the hinges of said door-sections, and a connecting rod pivotedly connected at one end to said link and at the other end to said crank, substantially as and for the purposes set forth.

In testimony, that I claim the invention set forth above I have hereunto set my hand this 20th day of April, 1910.

EDWARD M. MOLLER.
